GEORGE F. RITTER, OF CHICAGO, ILLINOIS, ASSIGNOR TO STROMBERG MOTOR DEVICES COMPANY, OF CHICAGO, ILLINOIS, A CORPORATION OF ILLINOIS.

CARBURETER.

1,206,916.

Specification of Letters Patent. Patented Dec. 5, 1916.

Application filed January 12, 1914. Serial No. 811,533.

To all whom it may concern:

Be it known that I, GEORGE F. RITTER, a citizen of the United States, residing at Chicago, in the county of Cook and State 5 of Illinois, have invented certain new and useful Improvements in Carbureters, of which the following is a full, clear, concise, and exact description, reference being had to the accompanying drawings, forming a 10 part of this specification.

My invention relates to an improved carbureter of the compensating type in which provision is made for maintaining a fuel mixture of uniform richness for varying 15 speed conditions of the engine supplied with fuel by said carbureter.

It is well-known in the art that a simple single jet carbureter will not supply a mixture of uniform richness for varying speeds 20 of the engine, but that the mixture becomes richer as the speed of the engine and, therefore, the demand upon the carbureter, increases.

My invention is further limited to the 25 class of carbureters in which an auxiliary air valve is used for the purpose of maintaining the mixture of uniform richness for the varying conditions referred to. In the past various devices have been suggested for 30 causing auxiliary air valves to operate without "fluttering" in response to the impulses of suction from the engine, and my invention has to do with an improved means for preventing such an operation of the auxiliary air valve, as a result of which it will 35 open and close according to the demand made upon the carbureter by the engine and for any given running condition it will remain practically quiet in such a position 40 as to permit the proper amount of air to pass through it for the running condition of the engine then obtaining.

The several drawings illustrating my invention are as follows:

45 Figure 1 shows my carbureter construction in vertical sectional view, the float chamber being shown in vertical elevation. Fig. 2 is a sectional view of the parts shown in Fig. 1, taken along the line 2—2. Fig. 50 3 is a top view of a control cam for the auxiliary air valve, taken along the line 3—3 in Fig. 1. Fig. 4 shows, in a view similar to Fig. 1, a modified construction of carbureter in which a single jet is employed of

such a construction as to compensate for 55 varying conditions of operation. Fig. 5 shows, in a view similar to Fig. 4, an enlarged vertical sectional view of the fuel jet used in Fig. 4.

Similar numerals refer to similar parts 60 throughout the several views.

Referring to the drawings, the carbureter consists of a main casing 1 connecting at its lower end with the main air supply passage 2 controlled by an intake throttle 65 valve 3, of the butterfly type, operated by a crank 4 by means of a connecting rod 5 extending to any desired point of control, as, for example, the dashboard of the vehicle when the carbureter is used in connection with an automobile engine. Centrally disposed in the body of the air passage extending vertically through the casing 1 is a Venturi tube 6 provided to increase the 70 velocity of the air at this point to produce 75 a proper aspirating effect upon the fuel nozzle 7. This nozzle is mounted in an upwardly extending arm from the cross rib 8 extending across the lower end of the main air passage through the carbureter, 80 and this rib is extended beyond the wall of the casing 1 to support a float chamber 9 which supplies the carbureter with fuel. The particular mechanism of the float chamber 85 constitutes no part of the present invention and, therefore, is not shown in detail. Liquid fuel, as, for example, gasoline, is supplied to the float chamber 9 by the supply connection 10 and communication is established between the float chamber 90 and the nozzle or jet 7 by means of holes 11 and 12 drilled through the rib 8 and the arm extending upwardly therefrom, the hole 11 being extended beyond the hole 12 into the lower end of a vertical hole or passageway 13 disposed at one side of the Venturi tube and main air passageway to supply fuel to the auxiliary nozzle or jet 14.

The mechanism of the float chamber 9 is so designed and adjusted as to maintain the 100 level of the liquid fuel in the float chamber just below the top or upper end of the nozzle 7, at substantially the level indicated by the broken line 15—16. The hole 12 is extended downward beyond the hole 11 105 through a downwardly projecting extension member from the rib 8, through the casing of the carbureter and communicates at its

lower end with a pet-cock 17 for draining the gasoline from the float chamber and carbureter when desired, the normal condition of this pet-cock during operation of 5 the engine being closed.

The nozzle 14 projects into an air passage 18 extending to one side from the main air passageway through the carbureter within an extension 19 formed from the side wall 10 of the casing 1 of the carbureter. A spider 20 extends into the top surface of the extension 19 so that it is in substantially horizontal position, and this spider carries a central boss 21 drilled vertically to receive 15 the vertical guide rod 22 of the auxiliary air valve 23. This valve 23 has projecting downwardly from its lower surface a tubular extension 24 of somewhat smaller diameter than the outside diameter of the 20 valve itself, and this tubular extension projects through the lower wall of the extension 19 into a tubular receptacle 25 having a bore of substantially the same size as the diameter of the tubular extension 24, as a 25 result of which the valve and its tubular extension may move freely in the receptacle 25 without allowing any substantial clearance between the moving parts. The receptacle 25 has projecting from its bottom a boss 26 30 drilled to support a rod 27 so that it may be freely moved vertically in said boss by a cam 28 pivotally connected to a vertical rod 29 rigidly secured in a boss 30 extending from the bottom of the receptacle 25, as 35 illustrated. A collar 30 secured to the lower end of rod 29 holds the cam 28 in position on said rod. An operating rod 31 is pivoted to a lever 32 extending to the left of the rod 29 from the cam 28 so that the 40 cam may be controlled from any distant point as desired.

The upper end of the rod 27 carries a circular block 33 having a central vertical bore to freely receive the lower end of the 45 rod 22, and this block has formed upon it a shoulder 34 upon which the lower end of the spring 35 rests, the upper end of this spring being in engagement with the lower surface of the valve 23 inside of the tubular extension 24. A second spring 36 is located 50 inside of the spring 35 with its upper end resting against the shoulder 37 projecting from the lower surface of the valve 23, and its lower end resting against a flanged collar 38 secured to the rod 22 above the upper end of the block 33. When the cam is turned the tension of the two springs may be successively increased. The receptacle 55 25 has drilled through its side walls, just above the bottom of said receptacle, a plurality of holes 39 so that the inside of the tubular extension is subjected at all times to substantially atmospheric pressure; and the portion of the lower surface of the valve 60 23 outside of the tubular extension 24 is sub-

jected to the suction developed in the air passage 18 by the running of the engine. As a result of this, any desired degree of differential action may be secured so that with the large upper surface of air valve 23, 70 which is found desirable in practice, the amount of surface exposed to the suction or partial vacuum created in the passageway 18 may be of any desired extent and by correspondingly proportioning the springs 35 75 and 36 any desired amount of opening may be secured for a given increase in the partial vacuum found in the air passage 18 for different running conditions of the engine. To regulate the operation of the valve, a spring stop 40 engaging notches 41 in the edge of the spider 20 is provided, so that by turning the spider 20 the tension upon the spring 35 may be varied without, however, changing the initial tension on the spring 36 since the rod 22 moves vertically with the spider 20 when the latter is adjusted. An independent adjustment of the spring 36 may be effected by manipulating the milled head 42 on the upper end of the 80 rod 22. The rod 22 is slidably mounted in the boss 21 and is supported by the engagement of the milled head 42 upon the top of the boss. Since the milled head 42 is threaded upon the rod 22, it may be adjusted relative to the rod, and the collar 38 85 raised or lowered, as desired. The head 42 is provided with a downwardly extending spline pin 42', which is adapted to engage in a corresponding pocket in the boss 21, as 90 illustrated in Fig. 1. This engagement of the spline pin in the pocket holds the head 42 against rotation and therefore prevents the head from being jarred out of adjustment. When it is desired to adjust the 95 height of the collar 38, the head 42 is raised so as to bring the pin out of the pocket and is then turned to the desired extent and then lowered so as to return the pin to the 100 pocket.

It will be obvious that if the collar 38 is sufficiently lowered, the top of the spring 36 may be spaced away from the under side of the valve. In such a case, what is known as a "pick up" action is secured— 115 that is, on the lower speeds the spring 35 constitutes the entire resistance to the opening of the valve, whereas on the higher speeds the valve is lowered sufficiently to bring the spring 36 into play to form an 120 additional resistance.

The auxiliary nozzle 14 being located in the path of the air supplied to the carbureter through the auxiliary valve 23 serves to supply to the carbureter a sufficient amount of fuel by its aspirating action so that the combined mixture formed in the upper part of the carbureter and supplied to the engine from the two air passages and the two nozzles will have a uniform rich- 125 130

ness for varying speeds of engine operation and correspondingly varying degrees of suction produced by the engine. The auxiliary nozzle 14 is provided with a small opening 43 communicating with an air passageway 44 extending through the horizontal wall 45 which supports the Venturi tube 6. The passageway 44 communicates with the atmosphere through a hole 46 formed in 10 the side wall of the carbureter casing, and the wall 45, being continuous, affords no passage for the incoming air from the passageway 2 except through the Venturi tube 6.

15 A clearance opening is provided around the nozzle 14 opposite the hole 43, which clearance opening is in connection with the passageway 44 so that the interior of the nozzle 14 is in communication with the atmosphere for any angular position of the hole 43. This provides that the hole 43 need not be disposed in any particular angular position in the nozzle to line up with the opening 44 when the nozzle is screwed 25 surely against its seat. The nozzle opening and the hole 43 are so proportioned that for the amount of suction or partial vacuum created in the upper part of the carbureter during starting conditions and low running 30 speeds of the engine, the air entering the nozzle 14 through the hole 43 will serve to nearly or quite prevent the supply of gasoline from the nozzle 14 to the air passing through the carbureter for these conditions.

35 When the valve 23 is opened, however, by an increase in the suction produced in the carbureting chamber, the aspirating action resulting from the rush of air across the end of the nozzle 14 sucks out the contents 40 of the nozzle more rapidly than air can be supplied to the nozzle through the hole 43, as a result of which gasoline is supplied by the nozzle 14 in such quantity, owing to the relation between the bore of the nozzle and 45 the size of the hole 43 that the combined mixture produced in the carbureter will have a substantially uniform richness for varying demands made by the engine. A throttle valve of the ordinary butterfly type 50 is disposed in the upper part of the mixing chamber of the carbureter to determine the amount of fuel mixture supplied by the carbureter to the engine for varying conditions 55 of load carried by the engine.

60 As a result of the construction described, the springs 35 and 36 may be so adjusted, if desired, that the carbureter will operate at starting substantially the same as a single jet carbureter, which condition may be continued for slow speeds of the engine, after which, as the engine increases in speed, the increased suction opens the air valve 23 an amount depending upon the said increase. Thereupon the inrushing air passing over 65 the valve 23 will tend to keep the valve in

substantially the same position for the particular running condition of the engine than obtaining, for, on account of the comparatively small amount of surface of the valve 23 exposed to the suction of the engine, the 70 springs 35 and 36 may be made comparatively light and the inertia of the valve will, therefore, tend to prevent its ready fluctuation or fluttering for the pulsations in the suction caused by the operation of the engine. In this way the adjustments may 75 readily be made such as to take care of any desired operating conditions. If, during any condition of operation, it is found that a richer mixture is required for a short 80 time than is supplied by the open position of the auxiliary air valve, the cam 28 is operated so as to move the block 33 upward, increasing the tension upon the spring 35 and bringing the block into engagement 85 with the lower end of the rod 22 to hold the valve 23 securely against its seat. By moving the cam 28 a small amount, it will be seen that the tension of the spring 35 may be changed somewhat without interfering 90 with a certain degree of opening of the valve 23, which condition may be desirable for certain conditions of operation.

95 In the construction shown in Fig. 4, the parts are similar to those shown in Fig. 1, with the exception that the auxiliary fuel nozzle is not employed and the main fuel nozzle 7^a is of such a conformation that the fuel flow therethrough varies in a manner to compensate for the varying degrees of 100 suction produced in the carbureting chamber, so that the mixture becomes leaner for increasing engine speeds. The nozzle 7^a, as shown in Fig. 5, is constructed with a Venturi tube delivery opening 7^b by which the 105 quantity of fuel flowing through the nozzle is caused to have an entirely different law of variation for varying suctions in the carbureting chamber from that which obtains with the regular form of nozzle shown in 110 Fig. 1. As a result, it is found that with this Venturi tube construction of fuel nozzle, the fuel delivered for low suction in the carbureting chamber is of sufficient quantity to produce a rich mixture which is desirable 115 for starting and for slow speeds of operation. When, however, the suction is increased by an increase in the engine speed, the fuel flowing from the nozzle is increased 120 in quantity in a greater proportion than would result from the use of a plain nozzle, owing to the Venturi tube at the discharge end of the nozzle, and therefore a richer mixture is the result, which is a condition 125 to be desired. This result is not accomplished wholly by the air flowing through the main air passages 2^a and 6^a, but by the air passing through these passages in addition to the air passing through the auxiliary air passage 18^a, which auxiliary passage is 130

controlled in the same manner as described above for the construction shown in Fig. 1. The effect of the Venturi tube fuel jet is therefore to deliver an amount of fuel which 5 increases to a greater degree than the increase in the amount of fuel delivered from the regular jet construction shown in Fig. 1 for varying changes of suction at the tip of the fuel jet, but when the mixture resulting 10 is modified by the auxiliary air introduced through the air passage 18, a progressively leaner mixture is the result as the engine speed increases. As a result of this construction, by properly proportioning the 15 fuel jet for the particular demands to be made upon the carbureter, all complication resulting from the use of an auxiliary fuel nozzle is done away with, and a much simpler and equally as effective construction is 20 the result. Furthermore, with the Venturi tube form of nozzle the advantage is secured that sufficient fuel is delivered to the carbureter to produce a proper mixture for high speed operation with a larger quantity 25 of air than could be properly carbureted for the same speed of engine with an auxiliary nozzle of the plain jet type shown in Fig. 1, assuming that said nozzles are both constructed to properly carburet the same given 30 volume of air for slow speed operation.

While I have shown my invention in the particular embodiment herein described, I do not, however, limit myself to this construction and exact arrangement of parts 35 as I may employ other and equivalent constructions without departing from the spirit of my invention.

What I claim is:

1. In a carbureter, the combination of a 40 casing, said casing containing a mixing chamber and having a main and an auxiliary air passage for supplying air thereto, and a valve for said auxiliary passage having a part of one of its surfaces subject to 45 the pressure in said auxiliary passage and the remainder of the same surface subjected to substantially atmospheric pressure.

2. In a carbureter, the combination of a 50 casing, said casing containing a mixing chamber and having a main and an auxiliary air passage for supplying air thereto, a valve for said auxiliary passage having a part of one of its surfaces subject to the 55 pressure in said auxiliary passage and the remainder of the same surface subjected to substantially atmospheric pressure, and a spring for normally holding said valve in its closed position.

3. In a carbureter, the combination of a 60 casing, said casing containing a mixing chamber and having a main and an auxiliary air passage for supplying air thereto, a valve for said auxiliary passage having a part of one of its surfaces subject to the 65 pressure in said auxiliary passage and the

remainder of the same surface subjected to substantially atmospheric pressure, a spring for normally holding said valve in its closed position, and devices for holding said valve in its closed position when desired. 70

4. In a carbureter, the combination of a 75 casing, said casing containing a mixing chamber and having a main and an auxiliary air passage for supplying air thereto, a valve for said auxiliary passage having a part of one of its surfaces subject to the pressure in said auxiliary passage and the remainder of the same surface subjected to substantially atmospheric pressure, and two independently adjustable springs for opposing 80 the opening of the valve.

5. In a carbureter, the combination of a 85 casing, said casing containing a mixing chamber and having a main and an auxiliary air passage for supplying air thereto, and a valve for said auxiliary passage having a cylindrical extension from one of its faces through said auxiliary passage to co-operate with a bore in the casing for freely receiving said extension whereby the cylindrical surface of the extension and the adjacent surface of the valve outside of said extension are subjected to the pressure in the auxiliary passage and the portion of the valve within the cylindrical extension is 90 subjected to substantially atmospheric pressure. 95

6. In a carbureter, the combination of a 100 casing, said casing containing a mixing chamber and having a main and an auxiliary air passage for supplying air thereto, a valve for said auxiliary passage having a cylindrical extension from one of its faces through said auxiliary passage to co-operate 105 with a bore in the casing for freely receiving said extension whereby the cylindrical surface of the extension and the adjacent surface of the valve outside of said extension are subjected to the pressure in the auxiliary passage and the portion of the valve within the cylindrical extension is 110 subjected to substantially atmospheric pressure, and a spring for normally holding said valve in its closed position.

7. In a carbureter, the combination of a 115 casing, said casing containing a mixing chamber and having a main and an auxiliary air passage for supplying air thereto, a valve for said auxiliary passage having a cylindrical extension from one of its faces 120 through said auxiliary passage to co-operate with a bore in the casing for freely receiving said extension whereby the cylindrical surface of the extension and the adjacent surface of the valve outside of said extension are subjected to the pressure in the auxiliary passage and the portion of the valve within the cylindrical extension is 125 subjected to substantially atmospheric pressure, a spring for normally holding said 130

valve in its closed position, and mechanism for holding said valve in its closed position when desired.

8. In a carbureter, the combination of a casing, said casing containing a mixing chamber and having a main and an auxiliary air passage for supplying air thereto, a valve for said auxiliary passage having a cylindrical extension from one of its faces through said auxiliary passage to coöperate with a bore in the casing for freely receiving said extension whereby the cylindrical surface of the extension and the adjacent surface of the valve outside of said extension are subjected to the pressure in the auxiliary passage and the portion of the valve within the cylindrical extension is subjected to substantially atmospheric pressure, two springs engaging said valve to oppose the opening thereof, and independent mechanism for adjusting the tension of each spring.

9. In a carbureter, the combination of a casing, said casing containing a mixing chamber and having a main and an auxiliary air passage for supplying air thereto, a valve for said auxiliary passage having a cylindrical extension from one of its faces through said auxiliary passage to coöperate with a bore in the casing for freely receiving said extension whereby the cylindrical surface of the extension and the adjacent surface of the valve outside of said extension are subjected to the pressure in the auxiliary passage and the portion of the valve within the cylindrical extension is subjected to substantially atmospheric pressure, two springs engaging said valve to oppose the opening thereof, and independent mechanism for adjusting the tension of each spring, said cylindrical extension being counter-bored to receive the ends of said springs.

10. In a carbureter, the combination of a casing, said casing containing a mixing chamber and having a main and an auxiliary air passage for supplying air thereto, a valve for said auxiliary passage having a cylindrical extension from one of its faces through said auxiliary passage to coöperate with a bore in the casing for freely receiving said extension whereby the cylindrical surface of the extension and the adjacent surface of the valve outside of said extension are subjected to the pressure in the auxiliary passage and the portion of the valve within the cylindrical extension is subjected to substantially atmospheric pressure, and a cup carried by the casing for receiving said cylindrical extension, said cup having one or more air openings near its lower end.

11. In a carbureter, the combination of a casing, said casing containing a mixing chamber and having a main and an auxiliary air passage for supplying air thereto, a valve for said auxiliary passage having a

cylindrical extension from one of its faces through said auxiliary passage to coöperate with a bore in the casing for freely receiving said extension whereby the cylindrical surface of the extension and the adjacent surface of the valve outside of said extension are subjected to the pressure in the auxiliary passage and the portion of the valve within the cylindrical extension is subjected to substantially atmospheric pressure, a spring for normally holding said valve in its closed position, and a cup carried by the casing for receiving said cylindrical extension, said cup having one or more air openings near its lower end.

12. In a carbureter, the combination of a casing, said casing containing a mixing chamber and having a main and an auxiliary air passage for supplying air thereto, a valve for said auxiliary passage having a cylindrical extension from one of its faces through said auxiliary passage to coöperate with a bore in the casing for freely receiving said extension whereby the cylindrical surface of the extension and the adjacent surface of the valve outside of said extension are subjected to the pressure in the auxiliary passage and the portion of the valve within the cylindrical extension is subjected to substantially atmospheric pressure, a spring for normally holding said valve in its closed position, mechanism for holding said valve in its closed position when desired, and a cup carried by the casing for receiving said cylindrical extension, said cup having one or more air openings near its lower end.

13. In a carbureter, the combination of a casing, said casing containing a mixing chamber and having a main and an auxiliary air passage for supplying air thereto, a valve for said auxiliary passage having a cylindrical extension from one of its faces through said auxiliary passage to coöperate with a bore in the casing for freely receiving said extension whereby the cylindrical surface of the extension and the adjacent surface of the valve outside of said extension are subjected to the pressure in the auxiliary passage and the portion of the valve within the cylindrical extension is subjected to substantially atmospheric pressure, two springs engaging said valve to oppose the opening thereof, independent mechanism for adjusting the tension of each spring, and a cup carried by the casing for receiving said cylindrical extension, said cup having one or more air openings near its lower end.

14. In a carbureter, the combination of a casing, said casing containing a mixing chamber and having a main and an auxiliary air passage for supplying air thereto, a valve for said auxiliary passage having a cylindrical extension from one of its faces through said auxiliary passage to coöperate with a bore in the casing for freely receiving

- said extension whereby the cylindrical surface of the extension and the adjacent surface of the valve outside of said extension are subjected to the pressure in the auxiliary 5 passage and the portion of the valve within the cylindrical extension is subjected to substantially atmospheric pressure, two springs engaging said valve to oppose the opening thereof, independent mechanism for adjusting 10 the tension of each spring, said cylindrical extension being counter-bored to receive the ends of said springs, and a cup carried by the casing for receiving said cylindrical extension, said cup having one or 15 more air openings near its lower end.
15. In a carbureter, the combination of a casing containing a mixing chamber and having an air passage leading thereto, and a valve for said passage having a part of 20 one of its surfaces subject to the pressure in said passage and the remainder of the same surface subjected to substantially atmospheric pressure.
16. In a carbureter, the combination of a 25 casing containing a mixing chamber and having an air passage leading thereto, and a valve for said passage having a cylindrical extension from one of its faces through said passage whereby the cylindrical surface 30 of the extension and the adjacent surface of the valve outside of said extension are subjected to the pressure in said passage and the portion of the valve within the cylindrical extension is subjected to substantially atmospheric pressure.
17. In a carbureter, the combination of a 35 casing containing a mixing chamber and having an air passage leading thereto, a valve for said passage having a cylindrical extension from one of its faces through said passage whereby the cylindrical surface of the extension and the adjacent surface of the valve outside of said extension are subjected to the pressure in said passage and the portion of the valve within the cylindrical

extension is subjected to substantially atmospheric pressure, and a cup carried by said casing for receiving said extension, said cup having one or more air openings through it near the bottom thereof.

18. In a carbureter, the combination of a 50 casing containing a mixing chamber and having an air passage leading thereto, a valve for said passage having a part of one of its surfaces subject to the pressure in said passage and the remainder of the same surface subjected to substantially atmospheric pressure, and a spring for normally holding the valve in its closed position.

19. In a carbureter, the combination of a 55 casing containing a mixing chamber and having an air passage leading thereto, a valve for said passage having a cylindrical extension from one of its faces through said passage whereby the cylindrical surface of the extension and the adjacent surface of the valve outside of said extension are subjected to the pressure in said passage and the portion of the valve within the cylindrical extension is subjected to substantially atmospheric pressure, and a cup carried by 60 said casing for receiving said extension, said cup having one or more air openings through it near the bottom thereof.

20. In a carbureter, in combination, a 65 chamber in which reduction in pressure is produced, an air inlet leading to said chamber, fuel-inlet means, and a valve in said air inlet, said valve having one face exposed to the atmosphere and a portion of the other 70 face exposed to the pressure in said chamber, the remainder of said second-named face being exposed to the atmosphere.

In witness whereof, I hereunto subscribe my name this 8th day of January, A. D. 85 1914.

GEORGE F. RITTER.
